UNITED STATES PATENT OFFICE

116,013

DESIGN FOR A TELESCOPE

Leo H. Brown, New York, N. Y.

Application April 14, 1939, Serial No. 84,291

Term of patent 7 years

To all whom it may concern:

Be it known that I, Leo H. Brown, a citizen of the United States, residing at 44 Gramercy Park North, in the city, county, and State of New York, have invented a new, original, and ornamental Design for Telescopes, of which the following is a specification, reference being had to the accompanying drawing, forming part thereof.

Figure 1 is a side elevational view of the telescope, showing my new design.

Figure 2 is a sectional view along line 2—2 of Figure 1.

I claim:

The ornamental design for a telescope, substantially as shown.

LEO H. BROWN.
